MEANS FOR OPERATING MULTIPLE SLIDING DOORS

George Delbert Hulbert, Los Angeles, Calif., assignor to Twentieth Century-Fox Film Corporation, Los Angeles, Calif., a corporation of New York

Application June 22, 1938, Serial No. 215,140

4 Claims. (Cl. 268—51)

This invention relates to door operating means and deals particularly with a means for opening and closing multiple sectional sliding doors.

The invention to be described hereinafter has been developed particularly for use in building motion picture sets as a labor saving device, but the device in its various forms may become useful in other fields where multiple sectional sliding doors may be used. In order to show the possibilities of the invention, it has been disclosed in more than one form.

The principal object of the invention is to provide means for opening and closing multiple sectional sliding doors that may be easily and quickly set up with a minimum of labor and material. Another object is to provide means of a character described that may be utilized repeatedly in different types of structures and may be installed and dismounted as a unit. Another object of the invention is to provide means for controlling multiple sectional sliding doors whereby the various sections of the door may be partially supported upon the opening and closing means and partially supported upon a track. Still another object is to provide means of the character described whereby the multiple sections of a sliding door arrangement may be supported and operated upon a single track. A further object of the invention is to provide a lazy tong arrangement for opening and closing multiple sections of sliding doors wherein the lazy tong arrangement is supported at an outer point upon a track that follows the path of said point in its extensible movement.

Other objects and advantages will become apparent as the description proceeds in conjunction with the drawings, in which:

Figure 1 is a fragmentary side elevation of a multiple sectional door arrangement showing one form of my invention for opening and closing the doors.

Figure 2 is a view similar to Figure 1, showing the doors fully retracted with the door opening clear.

Figure 3 is a view taken on line 3—3 of Figure 2.

Figure 4 is a side elevation of a multiple sectional sliding door arrangement showing another form of my invention for opening and closing the doors.

Figure 5 is a view similar to Figure 4, showing the doors fully retracted with the door opening in the clear.

Figure 6 is a view taken on line 6—6 of Figure 5.

Briefly stated, the invention embodies a lazy tong arrangement fixed to the wall or the structure of a building, or a motion picture set, over a door opening so that the various moving pivots of the lazy tong arrangement may be attached to the multiple sections of the door and operated to proportionally move the individual door sections to fully open and close the door opening. The lazy tong arrangement may be constructed as a unit and may even be mounted upon a base that may in turn be mounted on the structure containing the door opening. In this way the unit may be used repeatedly and may be easily and conveniently installed and dismounted. A unit of this nature is particularly useful in building motion picture sets.

Referring to drawings 1, 2 and 3, which show one form of my invention, it may be seen that I have more or less diagrammatically illustrated the installation of a lazy tong arrangement, generally designated 11, over a door opening 12. The structure upon which the arrangement may be mounted is immaterial, inasmuch as it is not a part of the invention. The relation of the door opening means to the door itself is disclosed to illustrate the invention. In these views it will be seen that the lazy tong arrangement 11 is mounted upon a base 13, which is suitably mounted upon the supporting structure designated as a wall 20, containing the door opening 12. The door opening 12 is adapted to be closed by a multiple sectional door containing in this instance three sections, 14, 15 and 16. In this installation the doors 14, 15 and 16 are supported upon tracks 17, 18 and 19 (see Figure 3), said tracks in turn being mounted upon the supporting wall 20 by means of a multiple bracket arrangement, generally designated 21. The doors 14, 15 and 16 are each supported upon tracks 17, 18 and 19 respectively by means of identical rollers 22 and brackets 23. This structure will be recognized as the ordinary track arrangement for supporting multiple sectional sliding doors. The means whereby these sections are moved proportionately to completely open and close the door opening 12 resides in the lazy tong arrangement generally designated 11. As is well known, a lazy tong arrangement consists of parallel bars pivotally inter-connected at spaced points. In this case my arrangement comprises parallel bars 24, 25 and a half bar 26. The other set of parallel bars is designated 27, 28 and 29. These bars are pivotally inter-connected at points 30, 31, 32, 33, 34, 35 and 36. The whole arrangement 55 is pivotally mounted upon the base 13 upon a

bracket support 37. The outer end of the arrangement carries a pivot point 38. The pivot points 32, 35 and 38 are connected by means of brackets 39, 40 and 41 to the doors 14, 15 and 16 respectively. It is to be understood that the brackets 39, 40 and 41 are rigidly connected to the doors. It will be seen, therefore, that as the lazy tong arrangement is extended or retracted the pivot points 32, 35 and 38 will move progressively increasing distances and will likewise carry the doors the same distances. The result is that if any one of the doors is moved the other doors are moved correspondingly. By properly arranging the reach of the lazy tongs, and by properly positioning the intermediate points on the tongs, any number of doors may be moved so as to properly position each section of the door to form a complete closure for a door opening. As an optional means of stabilizing the lazy tongs, I may incorporate a roller 43 arranged to ride upon a curved track 44 mounted upon the base 13 to hold the upper end of the lazy tong arrangement in a steady upright position when the device is in a closed position shown in Figure 2. In addition, I may even incorporate another roller 45 on the outer end of the arm 25 and install another curved track 46, which will give added stability and steadiness to the device. As a refinement, I may also embody a leaf spring 47, which is arranged to yieldingly engage the lazy tong arrangement in this case, shown as a point or the roller 45 on the arm 25. A spring of this nature will assist in the initial movement of the doors when starting to open them from a fully closed position and will also cushion the doors in the final closing movement. A device of the above nature may be readily and easily installed in conjunction with the ordinary installation of a multiple sectional door for opening and closing the doors and in the form shown may be readily dismounted and used again in other installations.

In Figures 4, 5 and 6 I have shown another form of my invention. In this form the device has been reduced to very simple construction and is so constructed that the multiple sections of the door may be operated upon a single track. The doors themselves are partially supported on the track and partially supported on the lazy tong arrangement, which also controls the sections in their opening and closing movement. In these views I have illustrated my invention as comprising a lazy tong arrangement generally designated 50 which is pivotally mounted upon a wall 51 in any suitable manner, as illustrated by a bracket 52. The wall in this instance may be a part of any structure and has a door opening 53. Over the door opening there is arranged a multiple section door comprising sections 54, 55 and 56. Each of these doors is supported at one edge by means of brackets 57, 58 and 59, which carry identical rollers 60 arranged to run upon a track 61. The track is supported upon the wall 51 in any suitable manner, such as by brackets 62. It will be noted that the brackets 57, 58 and 59 are shaped so as to throw the rollers into successive positions when the doors are closed, as shown in Figure 5. This will be observed to provide a support for the rear edge of each section. The front edges of the sections are supported on the lazy tong arrangement. In Figure 4 the lazy tong will be seen to comprise parallel bars 63, 64 and a short bar 65 crossing other parallel bars 66, 67 and 68. These bars are pivotally connected at mid points by the

pivots 69, 70, 71, 72, 73, 74, 75 and a forward single pivot point 76. This whole assembly, as before stated, is pivotally mounted on the wall 51 upon the bracket 52. The forward edges of the door sections 54, 55 and 56 are equipped with brackets 77, 78 and 79, which in turn are pivotally supported upon the pivots 71, 74 and 76 respectively. It is to be understood that these brackets are rigidly attached to the door sections and not only support the forward edges of the door but also operate to push the doors in and out on the track 61. It will be observed that the arm 79 is also equipped with a roller 80 adapted to run on the track 61. This roller gives support to the outer end of the lazy tong arrangement and holds the pivot points 71, 74 and 76 in line as the tong arrangement is extended and retracted. It can be seen, therefore, that as any one of the sections is moved the others are moved correspondingly and are supported and held in line by the lazy tong arrangement in combination with the track. If found desirable or necessary, the upper end of the lazy tong arrangement may be supported and held in a steady position by means of a guide track 81 mounted on the wall 51 and a roller 82 mounted on the pivot point 70. The track may be optional, inasmuch as the bars and the pivot points of the lazy tong arrangement may be made sufficiently strong to provide a steady arrangement that needs no upper support. A device of this character may also be installed as a unit and, if desirable, may be mounted on a base which carries the complete installation.

35 I claim:

1. For use in a structure having an opening adapted to be closed by multiple sectional sliding doors, a single track mounted on said structure over said opening, a lazy tong arrangement 40 having a point thereon pivotally mounted on said structure, means for movably supporting an outer extensible point of said lazy tong arrangement on said track, means for movably supporting one edge of each of said door sections upon said track, and means for supporting the opposite edge of each of said door sections respectively upon a series of extensible pivot points on said lazy tong arrangement.

2. For use in a structure having an opening 45 adapted to be closed by multiple sectional sliding doors, a single track mounted on said structure, a lazy tong arrangement having a point thereon pivotally mounted on said structure, means for movably supporting an outer extensible point of said lazy tong arrangement on said track, means for movably supporting one edge of each of said door sections upon said track, means for supporting the opposite edge of each of said door sections respectively upon a series of extensible pivot points on said lazy tong arrangement, and means on said structure for movably supporting an upper extensible point of said lazy tong arrangement.

3. For use in a structure having an opening 50 therein, a single track mounted on said structure over said opening, a lazy tong arrangement having a point thereon pivotally mounted on said structure over said opening, a roller mounted on an outer extensible point of said lazy tong arrangement adapted to ride said track, multiple sectional sliding doors adapted to cover said opening, individual rollers on said track adapted to support one edge of each of said door sections respectively, and means for supporting the opposite edge of each of said door sections re-

spectively upon successively extensible pivot points on said lazy tong arrangement.

4. For use with a structure having a door opening therein, a single track mounted on said structure over said opening, a lazy tong arrangement over said opening having one point thereof pivotally mounted on said structure, means for movably supporting an extensible point of

said lazy tong arrangement on said track, a plurality of sliding doors for closing said opening, means for movably supporting one edge of each of said doors on said track, and means for pivotally supporting the opposite edge of each of said doors upon separate extensible points of said lazy tong arrangement.

GEORGE DELBERT HULBURT.
